UNITED STATES PATENT OFFICE

JOHN P. RATHBUN, OF MOORES, PENNSYLVANIA, ASSIGNOR TO WESTINGHOUSE ELECTRIC & MANUFACTURING COMPANY, A CORPORATION OF PENNSYLVANIA

HEAT EXCHANGER

Application filed October 18, 1927. Serial No. 226,971.

My invention relates to tubular heat exchangers, such as surface condensers, tubular heaters, or coolers, and it has for an object, to improve the construction of apparatus of this character.

The exterior surfaces of the tubes, of a device of the type described, become fouled more or less rapidly, depending on the conditions of service. For instance, in oil heaters such as are used in oil refining, rather frequent, periodic cleaning is required. There are also many other classes of service in which the outer surfaces of the tubes must be cleaned quite frequently, if efficient performance is to be obtained.

With the devices of the prior art, so far as I am aware, it is necessary to remove the tube bundle from the shell of the heat exchanger in order to properly clean the outer surfaces of the tubes. Whether this procedure must take place quite frequently, or only at widely separated intervals, it is nevertheless quite burdensome, principally because it necessitates the breaking of various connections for the circulating media.

Furthermore, it is often desirable to provide heat exchangers of the type described with movable headers, so that the tubes may be rigidly secured in both tube plates.

More particularly, therefore, an object of my invention is to provide a heat exchanger of the type described, in which access may readily be had to the exteriors of the tubes for cleaning, or the like, and which shall embody a movable header which, while being suitable for various other heat exchangers, is well adapted to the particular construction of my heat exchanger.

Apparatus embodying the features of my invention is shown in the accompanying drawings, in which:

Fig. 1 is a sectional elevation of a heat exchanger; Fig. 2 is a transverse section taken along the line II-II of Fig. 1;

Fig. 3 is a fragmentary sectional view of a modified form of my invention showing one method of securing the floating head; and

Fig. 4 is a view similar to Fig. 3, but showing a still further modified form of my invention.

According to my invention, the shell of a heat exchanger is arranged to be separated longitudinally, and the inlet and outlet ports of the shell, as well as the supporting means therefor, are arranged on one of the separable sections. In this way, it is possible to remove the other separable member, or members, and to thus gain access to the exterior surfaces of the tubes. 55

Also, the movable head is arranged to be supported from the same shell section which carries the supporting means and which is provided with the inlet and outlet ports. Hence, by means of my novel construction, the tube nest is properly supported during 60 cleaning periods, as well as during the operation of the exchanger. 65

Referring now to the drawings, for a better understanding of my invention, I show a heater indicated generally at 10, and comprising a substantially horizontally disposed shell 11, within which is disposed a nest of tubes 12. The shell 11 is preferably formed of sections 13 and 14, which are arranged to be joined longitudinally in a substantially 70 vertical plane by means of the mating flanges 16. One of these sections, as the section 14, is provided with a vapor inlet connection 17 and a vapor discharge connection 18, and is also provided with supporting feet 19, for 75 supporting the heater upon any suitable foundation work. 80

The tube nest 12 is provided with a fixed tube sheet 21, which is disposed between the shell 11 and the inlet and discharge fluid box 22. The other end of the shell 11 is provided with a somewhat extended flange 23, to which is secured a suitable cover 24 for closing this end of the shell. Disposed at this end of the shell is a movable tube sheet 26, 85 to which is secured the return fluid box 27. The pressure in the return box 27 is often quite high, so that in case this box is secured to the tube sheet 26 by means of bolts or the like, it is necessary to space the bolts fairly 90 close together so as to provide a fluid-tight connection. 95

In order to provide a fluid-tight connection for the movable header 27, and at the same time to provide for movably support. 100

ing this header, I employ a suitable number of dowel bolts 28, for clamping the flange of the box 27 against the periphery of the tube sheet 26. The shanks, or doweled portions 5 of the bolts 28 are, preferably, arranged to extend into recesses 31, which are provided in the flange 23. In the arrangement shown, only two of such dowel bolts 28 are employed and the fluid box 27 is otherwise secured to the tube sheet 26 by means of bolts or the like (not shown) in a manner well known in the art. Also, the recesses 31 are disposed only in the section 14 of the shell so that, should the section 13 be removed, the tube nest would still 10 be movably supported by the dowels 29 from the section 14. While only two dowel bolts 28 are shown, it will be obvious that more than two may be used, should conditions render this advisable.

20 In the form of my invention shown in Fig. 3, the movable header 27 is supported in a similar manner, from the section 14 of the shell, by means of any suitable number of angle brackets 32, which are bolted or otherwise secured about the periphery of the movable tube sheet 26. The horizontally extending portion 33 of these brackets is slotted as at 34 to receive the dowel 36, which projects inward from the shell. In this way, the 25 brackets movably support the tube nest and by means of the pin and slot connection, it is assured that bending stresses will be avoided.

30 The arrangement shown in Fig. 4 is quite similar to that shown in Fig. 1 with the exception that dowel pins 37 are, in this instance, mounted upon the flange 23 of the section 14 of the shell, and these dowel pins are arranged to extend through holes provided in the tube sheet 26 and in the flange 40 of the return box 27. In this form of the invention, the weight of the movable end of the tube nest is carried by the dowel pins 37, which afford the necessary freedom of movement.

45 If desired, the heater may be provided with a baffle, such as baffle 38, which extends diagonally through the nest of tubes and is, preferably, secured to the respective tube sheets by means of brackets 39.

50 During periods of normal operation, my heat exchanger functions in a manner well understood in the art, the circulating media being passed from the inlet and discharge box 22, through the nest of tubes 12 to the return box 27, whence it is returned through the nest of tubes 12 to the inlet and discharge box 22, and discharged from the heater. Other media, such as vapor to be either heated or cooled, is admitted through the inlet connection 17 of the shell, and after passing 55 through the nest of tubes 12, it is discharged through the outlet connection 18 of the shell.

60 The baffle 38 is of the conventional type in which openings (not shown) are provided 65 near the ends of the tube nest in order to

permit gaseous media to pass from the lower to the upper side of the baffle.

It will readily be seen that, should it be desired to gain access to the exterior surfaces of the tubes for cleaning or the like, it is merely necessary to remove the section 13 of the shell and that, in so doing, it is not necessary to disturb the connections to the inlet and discharge box 22 or to the inlet and discharge connections 17 and 18, respectively, and that access may thus be had to the tubes without removing the tube bundle from the shell. The baffle 38, being secured by means of clips 39 to the respective tube sheets, may be removed after the shell section 13 is removed.

Furthermore, it will be observed that by providing a shell which is split vertically into the respective sections 13 and 14, it is assured that any refuse or the like which may collect in the bottom of the shell, either during cleaning periods, or at other times, will fall out of the shell of its own accord when the sections 13 and 14 are separated, whereas if the shell were split horizontally, it would be necessary to wash this refuse out of the lower portion of the shell.

It will thus be seen that I have provided a tubular heat exchanger in which access may be readily had to the tubes for cleaning their outer surfaces with a minimum of inconvenience. Furthermore, by means of my novel arrangement for supporting the movable tube sheet and the return fluid box, it is possible to provide a movable header type of heat exchanger with means for readily cleaning the outer surfaces of the tubes.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:—

1. A shell for a horizontal heat exchanger of the type described comprising fixed and removable sections joined longitudinally, the lower portions of said sections being joined along the lowermost portions of said shell, and means disposed laterally of and connected to said fixed section between the ends of the latter for supporting the entire shell.

2. A device as set forth in claim 1 in which the shell has inlet and outlet ports spaced apart circumferentially and only in said fixed shell section.

3. The combination with a heat exchanger comprising a shell, a nest of tubes therein, and tube sheets for the nest of tubes, a number of dowels extending through one tube sheet and adjacent the periphery thereof, and

means for supporting the dowels from the shell.

4. A horizontal heat exchanger of the type described comprising a shell, a nest of tubes within the shell, said shell comprising fixed and removable sections joined longitudinally, the lower portions of said sections being joined along the lowermost portions of the shell and means cooperating only with the fixed shell section for movably supporting one end of the tube nest.

5. A horizontal heat exchanger of the type described comprising a shell, a nest of tubes within the shell, said shell comprising sections joined longitudinally, the lower portions of said sections being joined along the bottom of the shell, means on one of said shell sections providing circumferentially spaced inlet and outlet connections for said shell, and means associated only with said one of said shell sections for movably supporting one end of the tube nest.

6. A device according to claim 5 in which means are provided only on said one of said shell sections for supporting the exchanger.

7. The combination with a horizontal heat exchanger of the type described comprising a shell having a flanged end, a nest of tubes within the shell, and tube plates for the tubes, of a return fluid box disposed adjacent one tube plate, and means for securing the return fluid box to said one tube plate and for movably supporting the tube nest and the return fluid box from the flanged end portion of the shell.

8. The combination with a heat exchanger comprising a shell, a nest of tubes therein, and tube plates for the tubes, of a return fluid box disposed adjacent one tube plate, dowel bolts for securing said return box to said one plate, and means providing recesses on said shell for slidably receiving said dowel bolts.

9. The combination with a horizontal heat exchanger of the type described comprising a shell constituted by fixed and removable sections joined longitudinally along the lowermost portions of the shell, a nest of tubes within the shell, tube plates for the tubes, a return fluid box disposed adjacent one tube plate, and means for securing said return fluid box to said one tube plate and for slidably supporting the tube nest and the return fluid box from only the fixed shell section.

10. A device according to claim 9 in which means are provided only on said fixed shell section and laterally thereof and between the ends of the latter for supporting the entire exchanger.

11. A device according to claim 9 in which inlet and outlet connections are provided only in the fixed shell section.

12. In a heat exchange device, the combination of an inlet and outlet water box, a tube nest, plate, and return box unit secured in place with respect to said inlet and outlet

water box, a semi-cylindrical shell section secured in place at one end with respect to the inlet and outlet water box, a cover section secured to the other end of the semi-cylindrical shell section, circumferentially spaced inlet and outlet connections associated with said semi-cylindrical section, a removable semi-cylindrical section secured at its ends to the inlet and outlet water box and to said cover and at its sides to said first semi-cylindrical section, and means for slidably supporting the end of the tube nest unit remote from the inlet and outlet water box entirely from said first cylindrical shell section.

13. In a heat exchange device, the combination of an inlet and outlet water box, a tube nest, plate, and return box unit secured in place with respect to said inlet and outlet water box, a cylindrical shell encompassing said unit and comprising a semi-cylindrical shell section secured in place at one end with respect to the inlet and outlet water box, a cover section secured to the other end of the semi-cylindrical shell section, inlet and outlet connections circumferentially spaced on said semi-cylindrical section, a removable semi-cylindrical section secured at its ends to the inlet and outlet water box and to said cover and at its sides to said first semi-cylindrical section, means carried by said first semi-cylindrical section for supporting the entire heat exchange device, and means for supporting the end of the tube nest unit remote from the inlet and outlet water box entirely from the first semi-cylindrical section.

14. In heat exchanger apparatus, the combination of a shell, a nest of tubes disposed within the shell, a tube sheet located at one end of the tube nest and fixedly secured to the shell, a floating tube sheet located at the other end of the tube nest, boxes associated with each tube sheet for circulating fluid through the tube nest, and means including dowels for supporting the floating tube sheet from the shell and providing for movement of said floating tube sheet relative to the shell.

In testimony whereof, I have hereunto subscribed my name this 11th day of October, 1927.
